CLAIM

The ornamental design for an aircraft wingtip position light, as shown and described.

DESCRIPTION

FIG. 1 is a front, top perspective view of an aircraft wingtip position light showing our new design and its environment; FIG. 2 is a detail rear, top perspective view thereof; FIG. 3 is a side view thereof; FIG. 4 is a front view thereof; and, FIG. 5 is a top view thereof.

The portions of the drawings shown in broken lines indicate surrounding structure and environment that forms no part of the claimed design.
